UNITED STATES PATENT OFFICE.

ARTHUR J. BRIGGS, OF SYRACUSE, NEW YORK, ASSIGNOR TO REMINGTON TYPEWRITER COMPANY, OF ILION, NEW YORK, A CORPORATION OF NEW YORK.

TYPE-WRITING MACHINE.

1,130,883.

Specification of Letters Patent.

Patented Mar. 9, 1915.

Application filed August 22, 1913. Serial No. 786,108.

To all whom it may concern:

Be it known that I, ARTHUR J. BRIGGS, citizen of the United States, and resident of Syracuse, in the county of Onondaga and State of New York, have invented certain new and useful Improvements in Type-Writing Machines, of which the following is a specification.

My invention relates to typewriting machines, and more particularly to the paper feed mechanism.

The main object of the invention, generally stated, is to provide paper feeding mechanism, which is simple in construction, inexpensive to manufacture, and efficient in use.

To the above and other ends which will hereinafter appear, my invention consists in the features of construction, arrangements of parts and combinations of devices, set forth in the following description and particularly pointed out in the appended claims.

In the drawings, Figure 1 is a transverse sectional view of one form of platen carriage equipped with paper feeding devices constructed in accordance with my invention, the paper feeding devices being shown in normal or operative position. Fig. 2 is a like view of the same, with parts omitted and parts broken away, this view showing the paper feeding devices released. Fig. 3 is a front elevation of the parts shown in Figs. 1 and 2.

As shown in the present instance, the carriage comprises a traverse or guide bar 1 having end plates or brackets 2 fixedly secured thereto and projecting upwardly therefrom. The end plates are united by a tie-rod 3 and are apertured at 4 to receive a platen shaft 5, the usual finger wheels being secured to the end of the platen shaft. A rotative platen 6 is mounted on the platen shaft and is provided with the usual platen heads 7 and 8, the latter of which is formed with line spacing ratchet teeth 9. A single piece sheet metal combined paper table and apron 10 extends from the rear side of the platen beneath the same and to the front thereof where it terminates at 11 below the printing line indicated by the dotted line X. The combined paper table and apron therefore extends from the introductory side of the platen to the front thereof just beneath the printing line, and in its normal position

is disposed, as shown in Fig. 1, with the forward edge of the paper apron bearing against the platen. The paper apron is apertured at 12, ears 13 being struck up and extending forwardly from the paper apron at the ends of each aperture 12. These ears are perforated for the reception of a pivot rod 14 on which are mounted paper feed rollers 15, the latter being arranged at the front of the platen and below the printing line. As shown, a roller is received between each adjacent pair of ears 13 and extends through the associated aperture 12 in the paper apron and into contact with the platen or the paper thereon.

The combined paper table and apron 10 is mounted for bodily movement fore and aft of the machine in the following manner: A cross rod 16 extends through the length of the carriage in the rear of the paper apron and is connected thereto by straps 17 which are riveted to the paper apron at 18. The cross bar is flattened at its ends and turned upwardly to form supporting arms or links 19 which are pivoted by shouldered pivot screws 20 to the inner sides of the end plates 2 of the carriage. The arms 19 constitute in effect substantially vertically disposed parallel links upon which the rear end portion of the combined paper table and apron is supported through the cross bar 16. The forward end portion of the paper table and apron is supported by a single centrally disposed sheet metal link, designated as a whole by the reference numeral 21. This link is also substantially vertically disposed and is pivoted at its lower end on a pivot rod 22 which is received in bearings in a sheet metal bracket 23 secured to the cross bar 1 by a screw 24. The upper end of the sheet metal link is turned around the pivot rod 14 of the feed rollers, as indicated at 25. It will be seen that this single sheet metal link 21 has a comparatively narrow pivotal bearing at its lower end, whereas the bearing portions 25 at the upper end of the link are widely separated in order to provide a comparatively broad pivotal bearing at the upper end of the link where it makes connection with the paper apron. The construction and arrangement of the links on which the combined paper table and apron is mounted are such that the combined paper table and apron is adapted to receive a bodily shifting substantially horizontal

movement fore and aft of the machine from the position shown in Fig. 1 to that indicated in Fig. 2.

The forward edge of the paper apron and the paper feed rollers 15 are normally maintained against the platen, or the paper thereon, by two leaf springs each of which is designated as a whole by the reference numeral 26. The upper end of each spring is secured by a screw 27 to the associated end plate 2, whereas the lower end portion of each spring is offset inwardly, as shown at 28 in Fig. 3, and is then extended forwardly and upwardly, as at 29 (Fig. 2), to the forward side of the cross bar 16. The force of each spring is exerted rearwardly on the cross bar to force the combined paper table and apron to the position shown in Fig. 1 and cause the paper feed rollers and the forward edge of the paper apron to bear against the platen. In order to release the feed rollers and the paper apron it is merely necessary to exert a forward pressure against the upper curved edge 30 of the paper table in the direction of the arrow in Fig. 1 and thus effect a movement of the member 10 and the parts carried thereby from the position shown in Fig. 1 to that indicated in Fig. 2.

I have provided a simple and efficient paper finger construction which is so combined with the paper apron that the paper fingers may be simultaneously released when the feed rollers are thrown off, as indicated in Fig. 2. The paper finger construction comprises a bar or support 31 which is angular in cross section and which is provided with integral bracket arms 32 by which the bar may be secured to the member 1 of the carriage by screws 33. The main body portion of the bar, which extends substantially throughout the length of the carriage, is disposed at an inclination, as shown in Fig. 1. The paper fingers are each designated as a whole by the reference numeral 34 and each paper finger and its supporting portion are formed from a single piece of spring sheet metal. The lower end of each paper finger is formed with a supporting or engaging portion 35. This portion partly surrounds the supporting bar 31 and conforms to the contour thereof so as to prevent the paper finger from turning on the bar but to enable it to be adjustable along the bar longitudinally of the platen. There is a spring pressure exerted by each paper finger against the platen or the paper thereon, and this, with the frictional resistance between the supporting portion 35 of each paper finger and the bar on which it is received, is sufficient to maintain the paper fingers against accidental displacement from the positions to which they may be adjusted longitudinally of the platen. From an inspection of Fig. 1 it will be seen that the

supporting bar 31 is situated directly beneath the paper feed rollers 15 and that each paper finger extends from said bar upwardly to a point above the printing line. Each paper finger is curved forwardly at 70 36 to form a pocket in the rear face of the paper finger, and in which the feed rollers 15 may be received. This is in order to provide a clearance between the paper feed rollers and the paper fingers which extend 75 upwardly in front thereof, so that the paper feed rollers 15 will offer no obstruction to the adjustment of the paper fingers longitudinally of the platen.

It will be understood from a comparison 80 of Figs. 1 and 2 that although the paper fingers 34 are supported independently of the paper apron, they extend adjacent to the forward edge 11 thereof so that when the latter is moved from the position shown 85 in Fig. 1 to that indicated in Fig. 2 the paper fingers will be simultaneously flexed and thrown off, irrespective of the positions to which they may be adjusted longitudinally of the platen. The feed rollers, the forward 90 edge of the paper apron and both paper fingers will, therefore, be simultaneously released from contact with the paper.

While I have shown my invention embodied in the present instance in a front 95 strike typewriting machine in which the type bars 37 are adapted to strike against the front face of the platen, it should be understood that the invention may be embodied in many styles of typewriting machines and that various changes may be made within the limits and scope of my invention.

From the foregoing description it will be understood that I have provided a paper 105 feed mechanism which is simple in construction, which is cheap to manufacture, and which is efficient in use, the construction comprising but few parts, most of which are formed from sheet metal and 110 can be readily assembled.

What I claim as new and desire to secure by Letters Patent, is:—

1. In a typewriting machine, the combination of a rotative platen, a paper apron 115 extending from the rear of the platen beneath the same and to the front thereof, and substantially vertically disposed swinging links arranged at different points fore and aft of the machine and on which said paper 120 apron is mounted for bodily substantially horizontal movement fore and aft of the machine.

2. In a typewriting machine, the combination of a rotative platen, a combined paper 125 table and apron extending from the rear of the platen beneath the same and to the front thereof, substantially vertically disposed swinging links arranged at different points fore and aft of the machine and on which 130

said combined paper table and apron is mounted for bodily substantially horizontal movement fore and aft of the machine, and paper feed rollers carried by said combined paper table and apron.

3. In a typewriting machine, the combination of a rotative platen, a combined paper table and apron extending from the rear of the platen beneath the same and to the front thereof, substantially vertically disposed swinging links arranged at different points fore and aft of the machine and on which said combined paper table and apron is mounted for bodily substantially horizontal movement fore and aft of the machine, and paper feed rollers carried by said combined paper table and apron at the front thereof and below the printing line, which rollers are released by a forward bodily movement of the combined paper table and apron.

4. In a typewriting machine, the combination of a rotative platen, a paper apron extending from the rear of the platen beneath the same and to the front thereof, a pair of substantially vertically disposed parallel links, a cross rod connecting said links and extending in the rear of the paper apron and to which the latter is connected, and a substantially vertically disposed link connected to the front of said paper apron.

5. In a typewriting machine, the combination of a rotative platen, a paper apron extending from the rear of the platen beneath the same and to the front thereof, substantially vertically disposed swinging links arranged at different points fore and aft of the machine and on which said paper apron is mounted for bodily substantially horizontal movement fore and aft of the machine, paper feed rollers carried by said paper apron at the front thereof and below the printing line, which rollers are released by a forward bodily movement of the paper apron, and springs operatively connected to said paper apron to effect a bodily rearward movement thereof and to maintain said paper feed rollers against the platen.

6. In a typewriting machine, the combination of a rotative platen, a paper apron extending from the rear of the platen beneath the same and to the front thereof, a pair of substantially vertically disposed parallel links pivoted to the carriage at the upper ends thereof, a cross rod connecting said links and extending in the rear of the paper apron and to which the latter is connected, springs operatively connected to said rod one near each end thereof for moving the paper apron rearwardly, and a substantially vertically disposed link connected to the front of said paper apron.

7. In a typewriting machine, the combination of a rotative platen, a paper apron extending from the rear of the platen beneath the same and to the front thereof,

substantially vertically disposed links on which said paper apron is mounted for bodily movement fore and aft of the machine, and paper fingers supported independently of the paper apron and which extend across the printing line and in front of the platen and which are moved away from the platen by the forward movement of said paper apron.

8. In a typewriting machine, the combination of a rotative platen, a combined paper table and apron extending from the rear of the platen beneath the same and to the front thereof, substantially vertically disposed links on which said combined paper table and apron is mounted for bodily movement fore and aft of the machine, paper feed rollers carried by said combined paper table and apron at the front thereof and below the printing line, which rollers are released by a forward bodily movement of the combined paper table and apron, and paper fingers supported independently of the combined paper table and apron and which extend across the printing line and in front of the platen and are moved away from the platen by the forward movement of said combined paper table and apron.

9. In a typewriting machine, the combination of a rotative platen, a combined paper table and apron formed from a single piece of sheet metal and extending from the rear of the platen beneath the same and to the front thereof, a pair of substantially vertically disposed parallel links, a cross rod connecting said links and extending in the rear of the combined paper table and apron and to which the latter is connected, a substantially vertically disposed link connected to the front of said combined paper table and apron, and paper fingers supported independently of the combined paper table and apron and which extend across the printing line and in front of the platen and which are moved away from the platen by the forward movement of said combined paper table and apron.

10. In a typewriting machine, the combination of a rotative platen, a combined paper table and apron formed from a single piece of sheet metal and extending from the rear of the platen beneath the same and to the front thereof, and paper fingers supported at their lower ends on the carriage for adjustment longitudinally of the platen and which extend across the printing line and in front of the platen and are moved away from the platen by the forward movement of said combined paper table and apron.

11. In a typewriting machine, the combination of a rotative platen, a paper apron extending from the rear of the platen beneath the same and to the front thereof, a pair of substantially vertically disposed parallel links for supporting the paper

- apron at the rear thereof, and a single centrally disposed substantially vertically arranged link for supporting the forward side of said paper apron.
12. In a typewriting machine, the combination of a carriage, a platen supported thereby, paper feed rollers arranged near the front of the platen and beneath the printing line, a bar fixed to the carriage and extending substantially throughout the length thereof below the printing line, said bar being angular in cross section, and paper fingers which are carried by and adjustable along said fixed bar and project upwardly therefrom across the printing line and forward of said feed rollers, each paper finger having formed integral therewith an engaging portion which partly surrounds said bar and conforms to the contour thereof so as to prevent the paper finger from turning on said bar and for maintaining the paper finger flexed against the platen, the pressure of the flexed paper fingers maintaining them against accidental displacement from the positions to which they are adjusted along said bar, each paper finger being bent to clear the paper feed rollers during an adjustment of said fingers.
13. In a typewriting machine, the combination of a carriage, a platen carried thereby, a paper apron, feed rollers, a pivot rod which supports said feed rollers on the paper apron, and links on which said paper apron is mounted, one of said links being pivoted at one end on the carriage and at the other end on said pivot rod for the feed rollers.
14. In a typewriting machine, the combination of a carriage, a platen carried thereby, a paper apron, feed rollers, a pivot rod which supports said feed rollers on the paper apron, and links on which said paper apron is mounted, one of said links being pivoted at one end on the carriage and at the other end on said pivot rod for the feed rollers, said last mentioned link having a comparatively narrow pivotal bearing at one end and a comparatively broad pivotal bearing at the other end.
15. In a typewriting machine, the combination of a carriage, a platen, a paper apron, means for supporting said paper apron for bodily movement, said means including a single centrally disposed link pivoted at one end to the paper apron near the front edge of the latter, the link being pivoted at its other end to the carriage, one end of the link having a comparatively narrow pivotal bearing and the other end having a comparatively broad pivotal bearing.

Signed at Syracuse, in the county of Onondaga, and State of New York, this 20th day of August A. D. 1913.

ARTHUR J. BRIGGS.
